METHOD OF AND MEANS FOR MAKING TUBES OF CELLULOID AND THE LIKE

Filed Nov. 14, 1928

FIG. I.

FIG. II

52 53 INVENTOR:

WILLIAM MENDEL,

WILLIAM HENDERSON,
By Arthur E. Page,
Attorney.

UNITED STATES PATENT OFFICE

WILLIAM MENDEL, OF BEVERLY, NEW JERSEY, ASSIGNOR TO SANITE CORPORATION, OF BURLINGTON, NEW JERSEY, A CORPORATION OF NEW JERSEY

METHOD OF AND MEANS FOR MAKING TUBES OF CELLULOID AND THE LIKE

Application filed November 14, 1928. Serial No. 319,279.

My invention relates to tube forming methods and means of the general class claimed in Letters Patent of the United States No. 1,661,451 granted to John N. Whitehouse March 6, 1928; whereby a sheet of suitable material is rolled, while immersed in a solvent bath having the capacity to soften the surface of the material, so that successive convolutions thereof are rendered coherent and merge in a solid tube. Such material may be celluloid, cellulose nitrate, cellulose acetate; other products of cellulose; or any suitable substance. Any suitable solvent may be employed; for instance, acetone for said celluloid and nitrate, and ethyl acetate, or a mixture of alcohol and ether, for said cellulose acetate. Such solvents quickly lose their efficacy by absorption of the sheet material, and moisture from it and the atmosphere, and it is the purpose and effect of my invention to maintain the efficacy of such baths by elimination of such solutes therefrom.

For instance, in the formation of tubes but four inches long, for fountain pens, by rolling sheets of celluloid .010 of an inch thick, four inches wide, and twelve inches long, in a bath of acetone; altho each sheet is immersed but five seconds, so much of the sheet material is dissolved in the bath that the initial solvent capacity of the latter is progressively lessened so rapidly that not more than twenty such tubes can be made before the solvent capacity of such bath becomes insufficient to render the successively wound convolutions of the celluloid coherent. Such pollution occurs even more rapidly if the celluloid includes powdered metal, fish scales, or other pigments which are usually employed to fancifully figure or color the celluloid. Moreover, such an acetone bath is so hygroscopic that it rapidly absorbs moisture not only from the celluloid but from the supernatent atmosphere and the bath is rendered inefficient when it absorbs as much as one and one-half per cent of water; such absorption being attained in a few hours when such atmosphere is only naturally humid.

As hereinafter described, my invention includes methods of and means for forcibly circulating the solvent to and from the sheet ma-

terial being formed into tubes, and to eliminate the deleterious material from the solvent by precipitating such deleterious material and distilling or decanting the solvent from such precipitate.

My invention includes the various novel features of procedure, construction, and arrangement hereinafter more definitely specified.

In said drawings; Fig. I is a diagrammatic, partly sectional, elevation of apparatus embodying my invention. Figs. II and III are diagrammatic elevations of apparatus including respective modified forms of my invention.

Referring to Fig. I, the bath 1, which may comprise acetone or any other suitable solvent of tube material, is maintained at approximately the level 2 in the container 3 in position to submerge the sheet of material 4, which is temporarily supported by the frame plate 5, to be wound on the rotary mandrel 7 under pressure of the idle rollers 8; said mandrel 7 being conveniently rotated by the chain wheel 10 which is connected by the chain 11 with the wheel 12 which may be turned by the crank 13. Said frame plate 5 is mounted upon the rock shaft 14 so that the winding mechanism may be lowered to the operative position shown or be raised to the idle position by the handle 15.

The solvent liquid is preferably continuously circulated in the container 3 during the winding operation by means which moves it to and from the celluloid. Such circulating means conveniently includes the inlet conduit 17 and the outlet conduit 18, the latter being controlled by the valve 19.

As shown in Fig. 1, said conduit 18 leads into the still 20 of sufficient capacity to maintain the desired quantity of the solvent 1 above the precipitate 22 which may be removed thru the discharge outlet 23 under control of the valve 24. Said still may be subjected to heat from any suitable source, for instance, the burner 25, so as to volatilize the acetone 1 from the residue 22 in said still, which residue includes water, celluloid, and the pigments aforesaid. Of course, in order to thus eliminate water from said solvent, it

is necessary to effect such distillation at a temperature below 212° F. The gaseous acetone passes from the still thru the conduit 27 to the worm 28 in which it is re-condensed to liquid form and from which it is received in the rotary pump 29 which discharges it back into the container 3 thru said inlet conduit 17. Said pump 29 is conveniently operated by the electric motor 30 which also 10 operates the air pump 32 for cooling said worm 28. Said motor is conveniently energized thru the conductors 34 under control of the switch 35; whereby the circulation of the solvent liquid and cooling of the worm 15 may be simultaneously controlled.

As a portion of the liquid contents of the circulatory system aforesaid must be continuously or intermittently wasted thru the drain 23; I find it convenient to include, in 20 the apparatus, a container 37 for fresh solvent which may be admitted to the inlet conduit 17 under control of the valve 38. However, whether the apparatus includes such container 37 or not; it is adapted to forcibly 25 move the solvent bath 1 to and from the celluloid 4 which is being formed into a tube and to maintain said solvent efficient during successive winding operations by the elimination of deleterious matter therefrom.

30 The distillation apparatus aforesaid is not only advantageous in that the solvent may be thereby continuously maintained at maximum efficiency by reason of the elimination of the deleterious material therefrom; but 35 because the freshly distilled acetone has a greater solvent effect upon the celluloid, per unit of volume, than commercial acetone.

As it might be assumed that the aforesaid greater efficiency of the freshly distilled solvent is due to increase in its temperature incident to the distillation process; I note that 40 repeated tests have shown that such increased activity is manifest even when the temperature of the freshly distilled acetone delivered 45 into the container 3 thru the conduit 17 is lower than the temperature of the bath 1. However, if the acetone is allowed to remain stagnant after such distillation, it loses the aforesaid increased solvent efficiency which 50 characterizes it when freshly distilled.

Altho I prefer to eliminate the deleterious matter from the solvent bath 1 by continuous circulation and distillation thereof as above described; such deleterious matter may be 55 eliminated, continuously or intermittently, with respect to the winding operation, by decantation. For instance, in Fig. II, the conduits 17 and 18 are part of a closed circulatory system including the pump 40 and the decanter 41. The water and celluloid, pigments and other deleterious matter 22 gravitate to 60 the bottom of said decanter 41 from which they may be continuously or intermittently discharged thru the conduit 42 under control 65 of the valve 43.

However, I prefer to employ the simple distillation apparatus shown in Fig. III, wherein in the still 45 is heated by fluid, such as steam or water, circulated thru the coil 46, and the vapors of distillation rise above the level 70 of the solvent bath container 3, thru the conduit 47, provided with the heat insulating covering 48, and are condensed in the conduit 49 by tap water supplied through the conduit 50, so that the condensate gravitates into said container 3. The deleterious matter 51 may be discharged from said still 45 thru the conduit 52 under control of the valve 53 and the bath be replenished with purified solvent from the container 54, under control of the 75 valve 55.

It may be observed that in each form of my invention above contemplated, the separation and purification of the acetone from the deleterious material is effected by gravity; the 80 heat of the distillation operation merely serving to facilitate such gravitational separation.

Therefore, I do not desire to limit myself to the precise details of the method and means for forming tubing, as herein set forth, as it 85 is obvious that various modifications may be made therein without departing from the essential features of my invention, as defined in the appended claims.

I claim:

1. The method of forming tubing, which comprises winding a sheet of material into a roll while immersed in a solvent initially having the capacity to dissolve said material, but which capacity is lessened by the solute 100 from said material, including the step of eliminating the solute from the solvent material; whereby such capacity of the solvent is restored.

2. A method as in claim 1; wherein the solvent is separated from its solute by gravitation.

3. A method as in claim 1; wherein heat is employed to facilitate the separation of the solvent from its solute.

4. A method as in claim 1; wherein, contemporaneously with the winding operation, the solvent is forcibly circulated to and from the sheet material.

5. A method as in claim 1; wherein the solvent is forcibly circulated to and from the sheet material and thru a separator device wherein the solvent is separated from its solute.

6. A method as in claim 1; wherein the solvent is separated from the solute, by the action of gravity and heat, during the forcible circulation of the solvent to and from the material for forming the tubing.

7. The method of forming tubing, which comprises winding a sheet of celluloid into a roll while immersed in a bath of a solvent material initially having the capacity to rapidly dissolve the surfaces of said celluloid exposed thereto, so that the successively 120 exposed surfaces of the celluloid are successively 125 exposed thereto, so that the successively 130

wound convolutions thereof are rendered coherent and form a solid tube, but said capacity is progressively lessened by the amount of solute in said bath; and removing said solute from said solvent during the winding operation; whereby said capacity of the solvent is maintained at the proper efficiency for continuous use.

8. Apparatus for forming celluloid tubing, including means for winding a sheet of celluloid in a roll while immersed in a solvent bath and means for forcibly circulating the solvent in said bath during the winding operation.

10 9. Apparatus as in claim 8, including solvent circulating and purifying means, comprising a still, and a condenser in cooperative relation with said still.

15 10. Apparatus as in claim 8, including solvent circulating and purifying means, comprising a pump, a still, and a condenser in cooperative relation with said still.

20 11. Apparatus as in claim 8, including solvent circulating and purifying means, comprising a still, and a condenser in cooperative relation with said still; and means for heating the still above the temperature of the surrounding atmosphere.

25 12. Apparatus as in claim 8, including solvent circulating and purifying means, comprising a pump, a still, and a condenser in cooperative relation with said still; and means for heating the still above the temperature of the surrounding atmosphere.

30 13. Apparatus as in claim 8, including solvent circulating and purifying means, comprising a still, and a condenser in cooperative relation with said still; and means for cooling said condenser.

35 40 14. Apparatus as in claim 8, including solvent circulating and purifying means, comprising a pump, a still, and a condenser in cooperative relation with said still; means for cooling said condenser; and means for operating said pump and cooling means, including a motor.

45 50 55 15. Apparatus as in claim 8, including solvent circulating and purifying means, comprising a pump, a still, and a condenser in cooperative relation with said still; means for cooling said condenser; and means for operating said pump and cooling means, including an electric motor; and switch means whereby the means for circulating the solvent and cooling the condenser may be simultaneously controlled.

60 16. A method as in claim 1; wherein the solvent is distilled from the solute at a temperature below 212° F.; whereby water is eliminated from the solvent.

65 In testimony whereof, I have hereunto signed my name at Burlington, New Jersey, this thirty-first day of October, 1928.

WILLIAM MENDEL.
